UNITED STATES PATENT OFFICE.

WILLIAM K. MITCHELL, OF YONKERS, NEW YORK

TEA BALL.

Application filed May 31, 1928. Serial No. 281,862.

This invention relates to tea balls. In using the tea balls now on the market, the ball is placed in the tea pot and when the water is poured over it, the string with its tag, which is usually colored, often falls into the water which is objectionable. Very often to prevent this, the user holds the string and sometimes becomes scalded when pouring the water over the ball. Again, in using the ordinary tea ball, when the tea is sufficiently brewed and it is desired to keep the brew at the desired strength, the ball must be taken out of the pot often resulting in the soiling of the clothing of the user and the cloth on the table due to the dripping of the liquid therefrom. The withdrawn ball owing to its soggy condition and color presents an unsightly appearance and the disposition of it becomes a problem. Furthermore, in marketing tea balls they are packed a dozen or more in a box and the strings of the ordinary tea balls, because of the disorderly manner in which it is necessary to pack them, becomes entangled causing annoyance and confusion.

I am aware that various attempts have been made to overcome some of the foregoing objections such as substituting an elongated metal handle in place of the string, and securing the tag end of the string to the neck of the bag necessitating the placing of a metal ring around said neck; but such attempts so far as applicant is aware have proved a failure.

A primary object of my invention is to draw the tea ball up out of the brew to keep the latter at the desired strength. Another object is to hide the bag from sight after it is withdrawn from the brew. Another object is to prevent the entangling of the strings of the balls when shipping the same for the market. Another object is to prevent the string and tag from falling into the liquid in the tea pot.

Other objects and advantages of my improved tea ball will appear from the description to follow taken in connection with the accompanying drawing in which—

Figure 1 is a side view of a transparent tea pot showing my improved tea ball as it appears immersed in the water.

Figure 2 is a view similar to Figure 1 showing the improved tea ball pulled up clear of the water and positioned under the cover of the pot.

Figure 3 is a side view of another form of my invention.

Figure 4 is a detail view of a tag with the hook at the end opposite the end at which the string is secured.

Figure 5 is a side view of the tea ball shown in Figure 1 showing the tag hooked to the bag for shipping.

Figure 6 is a side view of still another modified form of my invention.

Figure 7 is a side view of another modified form of my invention.

Referring to the various views of the drawing in detail, in Figure 1 is illustrated a glass tea pot 10 having a handle 11, spout 12 and cover 13 as is usual. While a glass pot is shown for the purpose of illustrating the invention, I contemplate the use of my improved tea ball with tea pots made of porcelain or other suitable material.

My improved tea ball comprises a bag made of fabric or other suitable material and consisting of a body portion 14, a base 15, and having the material at its upper end gathered together to form folds 16 or a neck 80 portion, which folds are secured together by means of a metal ring 17 formed of aluminum. Secured to this ring 17 is a string 18. The mounting of this string 18 is an important feature of the present invention. As will be seen from Figures 1 and 5, the string 18 passes loosely from the ring 17 downwardly along the exterior of the bag and passes through a loop 19 formed at a point adjacent the bottom or base 15 of the bag. It will be understood, of course, that the string 18 may pass into the interior of the bag at a point adjacent the base 15 and emerge therefrom again at substantially the same point, or a strip of material forming a loop may be secured to the bag at said point through which the string may pass if desired. Also the string 18 may pass into the interior of the bag at a point near the ring 17 and pass along the inside thereof and emerge therefrom at a point adjacent said base 15 and accomplish the same result.

Secured to the free end of the string 18 is a tag 20, which usually contains directions for use or advertising matter as desired, the end of the string 18 being clamped to a metal hook 21 fixed to one end of the tag.

In the form of the invention shown in Figure 3, the string 18 passes loosely through the ring 17 and is fixed to a loop 22 formed

at a point adjacent the base 15. It will be understood, of course, that the end of the string 18 may be secured to the bag at this point by stitching or in any other suitable or desirable manner.

Figure 6 shows a bag formed of fabric and having a square shaped body portion 23 entirely closed by a row of stitching 24 around its edge. In this form of bag, the string 18 is passed through a loop 25 formed at a point adjacent one corner of the body portion and passing loosely over the body portion 23 has its end fastened to another loop 26 formed at a point adjacent one of the opposite corners of said body portion.

With reference to Figure 7, the form of ball here illustrated comprises a bag similar to the bag shown in Figures 1 and 5, but has the folds 16 of its neck portion secured together by looping the end of the string 18 therearound as indicated at 27 instead of by means of a metal ring.

In using the improved tea ball, the bag is placed in the tea pot 10 and the end of the string 18 hooked over the open end of the spout 12. Water, as indicated at 29, is then added entirely immersing the bag, as will be seen from Figure 1, and the bag is permitted to remain therein until the tea is sufficiently brewed. When the tea is sufficiently brewed and it is desired to remove the ball from the water all that it is necessary to do is to pull on the string 18 and by reason of the peculiar mounting of said string the neck portion of the bag is drawn inwardly toward the base portion thereby forcing the bag to assume a collapsed or substantially flat position, which readily fits under the cover 13 as appears from Figure 2, and clear of the water, and when a pot of nontransparent material, such as porcelain is used, the collapsed bag is out of sight. The bag is held in this collapsed position under the cover by reason of the weight of the cover 13 which clampingly engages the string.

In packing the balls for shipping the hook 21 is forced into the material of the bag thereby eliminating any free end which might become entangled with any other string in the box. While the hook 21 is

shown in Figures 1, 3, 5 and 7 as secured to the end of the tag at which the string is secured in order to permit the handling of the tag without injuring the fingers, said hook may be mounted on the opposite end of the tag as shown in Figure 4 in order to give the tag a more pleasing appearance if desired. The present invention contemplates, of course, the use of such a hook with the ordinary type of tea ball which has the string secured to its neck portion only.

While I have illustrated and described several embodiments of my invention, I desire it to be understood that various minor changes in the details of construction, proportions and arrangements of parts may be resorted to without departing from the spirit of the invention and sacrificing any of the advantages thereof and I desire to be limited only by the state of the prior art and the appended claims.

I claim:

1. A tea ball comprising a bag for holding a quantity of tea and a string secured to one end of said bag passing loosely therealong and through the opposite end thereof. 75

2. A tea ball comprising a bag having neck, body and base portions and a string having one end secured to said neck portion passing loosely along said body portion and through 80 said base portion outwardly of said bag.

3. A tea ball comprising a bag, a string secured to one end of said bag passing loosely therealong and through the opposite end thereof and a tag secured to the free end of 85 said string.

4. A tea ball comprising a bag, a string having one of its ends fixed to said bag, a tag, and a hook member mounted on said tag, one end of said hook member being secured 90 to said tag and forming means for clamping the free end of the string to said tag and the other end of said hook member having a pointed rounded portion for detachable engagement with said bag or a tea pot. 95

In testimony whereof, I hereunto affix my signature.

WILLIAM K. MITCHELL.
